US00D962792S

(12) **United States Design Patent** (10) Patent No.: **US D962,792 S**
(45) Date of Patent: ** Sep. 6, 2022

(54) **THERMOSTAT**

(71) Applicant: **BELIMO Holding AG**, Hinwil (CH)

(72) Inventors: **Walter Jungen**, Adliswil (CH); **Pascal Gerner**, Wetzikon (CH)

(73) Assignee: **BELIMO HOLDING AG**, Hinwil (CH)

(**) Term: **15 Years**

(21) Appl. No.: **35/511,099**

(22) Filed: **Jul. 6, 2020**

(80) **Hague Agreement Data**

Int. Filing Date: **Jul. 6, 2020**

Int. Reg. No.: **DM/209189**

Int. Reg. Date: **Jul. 6, 2020**

Int. Reg. Pub. Date: **Jan. 8, 2021**

(30) **Foreign Application Priority Data**

Jan. 24, 2020 (CH) 145139

(51) LOC (13) Cl. 10-04

(52) U.S. Cl.

USPC **D10/50**

(58) **Field of Classification Search**

USPC D10/50

See application file for complete search history.
